Samuel Setton
Setton's Patent

The Specification referred to in these Setton's Patent and Marking Party
in some containing a description in the word of the said invention
the subject of his improvement in the marking called the Union
or Strut.

A machine is for threshing or separating by raking the seed from
all kinds of grain from the straw stalk & cut stock at wheat corn
cereals, etc. also barley, rye, etc and also threshing all kinds
of grain in the following manner:—There are four sets of the
straws to stand on the outside sets are the shortest, there are
small posts joined into the middle of the side supports of the
sets, from the roof of posts springing the machine. The rollers are
apron or belt of rollers or wheels between these two rows of posts
there is a frame or carriage locked into the middle of the supports and
is in building or rods passes through this frame lengthwise, and along
one of the machine & passes through the feet of the Springs that are
locked to the rollers or cylinder & the Springs are con-
nected by bolts in the middle to the middle of the frame of the machine
and this makes from acting Springs at each end.

The before mentioned rods are for the purpose to
sabot or shield on the frame of the apron to prevent with short iron
copper or tin & holes cut through large enough for the stock to
travel through after it is cut off the stalk & cut there
are catches raised on the upper side of the iron & between the holes to
the hold of the grain, and passing between the roller & apron & these
catches being raised the iron the more & greater. The roller is
made of the same material and resembles a roller on the outside iron
one is a short paper the roller lengthwise & wear on and is a
pulley to give the roller its revolving motion. There are two pins on

on this shaft. It connects to a pinion above the roller by a piece of metal, but goes from each pinion to the frame. There are two rows that pass over this frame, & are connected to another frame, but is articulated so that, together, they rock on the roller to which it is attached. The roller revolves & vibrates at the same time, the frame on these vibrates. This is in opposition to when the roller slides one way the frame slides the other way. This produces the cutting & first vital principle of the machine. I claim this principle as my own discovery for the purpose herein described. And I claim this in the making of rollers upon a shaft, & when a wood or any kind of material is laid on this principle. At one end of the machine are posts of wood, & these are fastened to the middle post & is to support the feeding. At the other, there are two blocks of wood that the clothes pass round & one of the rollers & near the end is a pulley to give the feeding pulley its motion.

At the other end of the machine, opposite yester, is support the main shaft by which crank &c. the fly wheel is on an end of the shaft and near the wheel is the pulley to give motion to the other end is the crank. The end of the pulley is fastened to the crank & the other end is connected to the first beam.

This beam is horizontal. There is a shaft joint, so this beam & at the other end of this shaft is the second beam & is perpendicular. Then is a connecting rod goes from the second to the third beam. It is connected & held by pins & rivets. This rod gives a lever, vibrating, which is made to rock upon and roller in case the grain is damp or hard of operation, or shortens the vibration which by letting the roller down in case the grain is green to dry & give it a better operation. This lengthening and shortening the vibration system, I claim as my own discovery for the purpose. But, my claim is submitted to the Second vital principle.

The third beam has a shaft which passes through the middle of the fourth beam & extends a portion to the fourth beam, so the fourth beam

over power & motion are both over & there is a connecting rod going from the top end of the journal bearing to the roller & fastened by a pin and there is a connecting rod attached to the bottom end of the journal bearing & to the upper or shell B by the journal bearing acting in a 'valence' at the middle it causes the rotation of both upper & lower when in operation. At first, we feel to give the whole motion to the machine we connected an upright piece of wire and attached a weight to it.

The banca paper round this wire and then round
is passing on the main shaft & here round the pulley that is on the
shaft of the roller & then round the pulley, not giving motion to the joi-
nting cloth & then back making extra pulleys that are under the upper
deck to when it first began. Then the machine being put in the
time, the grain is spread on the feeding table & carried to the
under the roller then revolving, causes the grain between, i.e. the roller
is & the upper; then both roller & upper having their fine motion
or vibrating the former & rubbing motion the grain is taken to
where the roller & upper & the seed a former is rubbed off or broken
it goes to the stone table &c. The seed then passes into the holes in the
upper and falls down to the side board a ironed place & so pass
up under the rest part of the machine the stone & paper then the
stone & out of the machine to another place.

The particular properties or principles of this machine
at my own invention or discovery & they claim to the exclusive right
to the same. First principle is the revolving of rollers & vibrating
of rollers & upper, or shells at the same time preventing the rubbing
principle before stated to rub the seed or round off the stone table
etc. Second principle is the straightening the vibrating stroke, or the
long of the rollers & upper or shells &c. in case the grain be dry
or want of operation or of straightening the vibrating stroke, or motion in
case they grain be dry and in good order for operating. Third principle is
the general form of width and construction of the whole machine to
give the first principles mentioned.

All of the above specified apparatus, & claims

United States Patent

Patent No.: X5169

as my own invention or discovery for the purposes herein specified.
